UNITED STATES PATENT OFFICE.

JOHN O. PHELPS, OF LOS ANGELES, CALIFORNIA.

SAFETY RAIL-JOINT FASTENER.

Application filed November 16, 1923. Serial No. 675,103.

To all whom it may concern:

Be it known that I, JOHN O. PHELPS, a citizen of the United States, residing at Los Angeles, in the county of Los Angeles and State of California, have invented new and useful Improvements in Safety Rail-Joint Fasteners, of which the following is a specification.

This invention relates to safety rail-joint fasteners.

One object of the invention is to provide a boltless fastener.

Another object is to provide a fastener consisting of practically two pieces, both of which are identical and each of which is adapted therefore to be used in either right-hand or lefthand position as arranged in a set for clamping the ends of rails.

Another object is to provide a joint fastener which not only provides means for clamping the contiguous ends of rails but further forms a rigid chair to eliminate what is known as loose and low joints.

Another object is to provide a joint fastener which will provide for the natural expansion and contraction of the rails.

Another object is to provide a fastener component which may be readily cast or forged, and which component is in one-piece form and without joints or attached elements of any kind.

A further object is to provide a rail-joint fastener consisting of a pair of identical clamp members operative mutually on each other to act wedge-fashion in the clamping or gripping of the rail-ends.

Other objects and advantages will be made manifest in the following specification of an embodiment of the invention illustrated in the accompanying drawings, wherein:

Fig. 1 is a perspective of a completed rail-joint of the present invention.

Fig. 2 is a perspective of one of the joint members.

Fig. 3 is a plan of one of the members.

Fig. 4 is a cross-section showing the adaptation of the joint fastener to a double track installation.

The fastener of the present invention includes a pair of identical chairs and clamp-members each of which has a central body 2 having a plane top face on which the base B of a rail is adapted to rest. To one side of the body 2 there is formed a lateral under-grooved jaw 3 overhanging a recess 4 extending along the lateral body part 2^a.

This jaw inclines as indicated at a Fig. 3, as is also the side clamping-wall 3^a of the jaw. Along the opposite side of the body extends an elongated jaw 5 having a pressure or friction edge 5^a to bear up against the web W of the rail R. The top edge 5^b of the jaw 5 fits close up against the bottom of the ball of the rail. The jaw 5 has a set-back in a face 5^c to provide clearance from the rail-web and is also provided with a gripping-face 5^d inclined to conform to the inclination of the top surface of the rail-base B as is clearly seen in Fig. 1.

One end of each clamp-member is provided with the rail-chair 2 and is also provided with spike-receiving flanges 6 perforated at 7 to receive spikes driven into the usual rail ties. Preferably the spike-holes are offset, as in Fig. 3, to reduce splitting tendency, as would occur if the spike-holes were in alignment and the spikes driven therethrough into the tie.

The jaw 5 of each clamp-member gradually tapers forward from the body-end and the bottom surface 5^e of each jaw is substantially in the same plane as the surface 4^e of each body portion and which surface forms the bottom of the recess 4 under the clamp-hook or jaw 3. The chair-body 2 has a diagonal inner end-face 2^b, and this intersects the inner face 5^b of the lower portion of the jaw 5 and which sets back under the shoulder 5^d as clearly shown in Fig. 2. This face 5^b is parallel with the top face 5^a of the jaw, but is set back sufficiently to clear the edge of the base of the rail which is positively engaged only by the face 5^d and the corner surfaces 5^a and 5^b at the top of the jaw.

To effect a positive contracting and gripping action of one clamp-member as to the other when these are assembled in opposite relation as is shown in Fig. 1, the overhanging inner end of each jaw 5 is provided with a longitudinally extending channel 8, Fig. 1, the inner wall of which inclines complementarily with the inclination of the wall 3^a of the hook-jaw 3, so that, when the overhanging end of the jaw 5 of one member is thrust into the recess 4^a of the other member, the hook part of the jaw 3 enters the recess 8 in the jaw-horn 5. The taper of the hook 3 and of the horn-end 5 is of such angle as to relatively shift the two members forming the fastener laterally together or toward each other with

the result that when the fastener has been positioned under and around meeting ends of the rail, as shown in Fig. 1, then, as the two members are driven one into the other 5 by a longitudinal movement, they will relatively contract and, in a vise-like manner, clamp upon and firmly grip the interposed rail-ends. Preferably the angle of the hook 3 and the tapering horn 5 are such as to 10 grip in a positive manner and remain in locked position practically free from any loosening tendency. It will be seen that when the fastener members are set up, the top portion of each jaw 5 bears up against 15 the lower surface of the ball of the rail on each side of the web W, and the surfaces 5^a of each clamp-member bear down and inwardly on the top inclined faces of the bases B of the rails, the hook 3 of each of 20 the members engaging the horn or overhanging end of the jaw 5 at the inner face of the channel or groove 8, as clearly shown in Figs. 1 and 4.

In Fig. 4 the device is shown for the fastening of a pair of track rails set in close position. In such installations an intermediate elongated block or filler F is introduced between the spaced rails R and through the rails and the block there is 25 passed the usual fastening-bolt or bolts A. In this case of double track, the chair or body part 2 is made sufficiently wide to receive the bases or partial bases B of the rails; one rail being supported by the jaw 35 5 of one member, while the other track is supported and clamped by the horn 5^a of the other member which is driven in under the complementary hook 3.

In cases where the fastener is to be used 40 in securing the meeting ends of rails forming a part of a curve in a track, the faces 5^a of the jaws are preferably recessed as at 9 to clear the corners formed at the ends of the rails and to allow these corners to 45 slightly deflect by projection into the recesses 9.

From the above it will be seen that I have provided a safety rail-joint fastener of 50 extreme simplicity, of great strength, and of ease of application and adjustment and tightening up, and that I have provided a fastener which will provide for expansion and contraction and is at the same time entirely devoid of bolts and fish-plates and 55 which not only forms the means for effec-

tively fastening rail-ends, but also for supporting rail-ends as in a chair.

A very important advantage of the present invention is that the device consists essentially of what might be called a "one-piece" article of manufacture, since it is possible to use each piece in a right or lefthand position to complete the rail fastener. 60

Further embodiments, modifications and 65 variations may be resorted to within the spirit of the invention.

What is claimed is:

1. A safety rail-joint fastener, comprising 70 a pair of substantially identical gripping members having mutually wedging action to clamp upon rail-ends, each member including a transverse end body-portion having at one side a hooking part and at the other side a jaw part and each jaw 75 having an overhanging horn for wedging cooperation with the hook of the companion member in a fastener.

2. A safety rail-joint fastening member, 80 including an intermediate body-portion having at one side a jaw-like hook and at the opposite portion an elongated jaw having an overhanging projecting horn-portion recessed in one face to engage the jaw-like hook of a companion member forming a fastener, the jaw-like hook and the horn having complementary inclined faces operating to contract assembled members when telescoped one into the other. 85

3. A safety rail-joint fastening member, 90 including an intermediate body-portion having at one side a jaw-like hook and at the opposite portion an elongated jaw having an overhanging projecting horn-portion recessed in one face to engage the jaw-like hook of a companion member forming a fastener, the jaw-like hook and the horn having complementary inclined faces operating to contract assembled members when telescoped one into the other, the jaw and horn 95 of each member having surfaces to engage 100 in the angle at the intersection of the web and shoulder of the ball on one side of a rail, and having an effective face to engage the contiguous top surfaces of the base of 105 the rail.

In testimony whereof I have signed my name to this specification.

JOHN O. PHELPS.
